(57) **CLAIM**

The ornamental design for a lighting fixture, as shown and described.

DESCRIPTION

FIG. 1 is a perspective view of a lighting fixture, showing my new design from the bottom, side and one end;

FIG. 2 is a perspective view thereof, from the top;

FIG. 3 is a perspective end view thereof, the opposite perspective end view being a mirror image of that shown;

FIG. 4 is a perspective side view thereof, the opposite perspective side view being a mirror image of that shown;

FIG. 5 is a perspective top view thereof; and,

FIG. 6 is a bottom plan view thereof.
